UNITED STATES PATENT OFFICE.

HERMAN H. OSWALD, OF FORT ANN, NEW YORK.

RELOADABLE CARTRIDGE-FUSE.

Specification of Letters Patent. Patented Mar. 23, 1915.

1,133,175.

Application filed June 18, 1912. Serial No. 704,322.

To all whom it may concern:

Be it known that I, HERMAN H. OSWALD, a citizen of the United States, residing at Fort Ann, in the county of Washington, State of New York, have invented a certain new and useful Improvement in Reloadable Cartridge-Fuses, of which the following is a specification, reference being had therein to the accompanying drawing.

10 My invention relates to inclosed tubular or cartridge fuses, and has for its principal objects to do away with the waste of the outer casing after a fuse has blown, and to provide means by which the cartridge or 15 casing can be easily reloaded without the use of tools.

Briefly stated, I attain my object by surrounding the fusible strip or link with refractory or granular material inclosed in a 20 paper envelop so as to form a complete and self-contained unit independent of the outer casing.

My invention is illustrated in the accompanying drawings in which:

25 Figure 1 is a longitudinal section of a cartridge fuse embodying my invention. Fig. 2 is a longitudinal section of the tubular casing of the fuse. Fig. 3 is a face view of one of the end disks, and Fig. 4 is a side view of the "reload" or charge, including the fusible strip shown in dotted lines.

Referring to the drawings, A is a tubular shell or casing carrying threaded brass end rings B to receive the end rings B' which 35 secure in place the slotted end caps A'. The rings B may be secured upon the tube by screws b or in any other desired and suitable manner, and it is to be noted that the caps A' are provided with vents a' which lie 40 within the edges of the rings B'. The inner frangible envelop breaks at these vents, thereby permitting the escape of the gases and reduction of the internal pressure. One end cap A' is shown in Fig. 3, having six 45 vents a' and a diametral slot $\frac{1}{2}$. These slots are to pass the flat copper terminals and in order to aline them at both ends, the ends of both slots take over projections a on the opposite ends of the casing, as shown in 50 Fig. 2, and indicated in dotted lines in Fig. 3.

The charge or "reload" is shown removed from the tube in Fig. 4, and inserted therein in Fig. 1. It comprises an envelop F pref- 55 erably of asbestos paper, in cylindrical form,

with closed ends, which is packed with filling material L, a granular refractory material, surrounding the fuse strips or links J which extend axially through the paper cylinder and are secured to copper terminals j. Inside of the end caps and the ends of the paper envelop transverse pins j^2 pass through the copper terminals, and outside of the end caps and the ends of the envelop parallel pins j' are also secured in the terminals, being spaced away from the envelop by just the thickness of the disks A', so that when the cartridge is loaded as shown in Fig. 1, and the end caps and rings are in position, the pin j^2 will rest against the end walls of the envelop and press them against the end caps, while the pins j' will lie outside the caps, and prevent any end motion of the fuse in the granular material L. It will be noted that not only is end 70 motion thus taken up, but the flat terminals are rigidly secured to the tube A so they can not twist or turn. All stresses which occur in the terminals when the fuse is placed in or removed from a circuit are 75 taken up by the end caps, being communicated thereto directly in part and through the pins j and j' in part.

I am aware that many changes and modifications may be made in the device which I have thus described, without departing from the spirit of my invention; and I wish it distinctly understood that I contemplate all such changes or modifications as fall within the scope of the appended claims. 85 For example, while the casing A is shown cylindrical and is preferably of fiber, it may be made in other shapes or of other material; while the end caps are secured by rings B and B', other means may be employed; while asbestos paper is mentioned for the envelop F, and end strains are taken up by pins j' and j^2 , these parts may be replaced by others of different materials or different forms. So also the end rings B 90 and B' may be made of any desired material, the pins j' may be placed inside or outside of the envelop F, and the projections a may be placed on the end caps A' and the coöperating slots on the tube body A. The 100 characteristic and essential feature of the invention is to have a "reload" or self-contained unit charge independent of the casing, so that the latter can be used more than 105 once.

Having thus described my invention, what I claim and desire to secure by Letters Patent is:—

1. A reloadable cartridge fuse comprising a tubular casing A, vented end caps for the tube, an inner paper envelop F, a fuse link J with terminals j projecting from its opposite ends, and pins or studs j'—j" in the terminals j, lying without and within the end caps respectively and adapted to engage the outer and the inner faces of the end caps when the fuse is loaded.
  2. In an electric fuse, an outer cartridge container of infrangible material, together with an inner envelop of frangible material snugly fitting within said outer container and inclosing a fuse link having projecting and exposed terminals, said container having apertures in its walls extending to the walls of the inner envelop whereby the inner envelop is without external support in the region of each aperture and points of fracture thereof are defined at the apertures.
  3. In an electric fuse, an outer cartridge container of infrangible material, together with an inner envelop of frangible material snugly fitting within said outer container and inclosing a fuse link having projecting and exposed terminals, said container having apertures in its end walls extending to the end walls of the inner envelop, whereby the areas thereof opposite the apertures are without external support and points of fracture thereof are thus defined.
  4. An electric fuse comprising a cylindrical tube of insulating material, concentric conducting sleeves permanently secured to the ends thereof and transversely flush with the same, flat end caps bearing against said sleeves, and a flanged ring threaded onto each sleeve and clamping said flat caps between their flanges and the ends of said metallic sleeves, together with a removable fuse link within said cartridge having end terminals projecting through and secured to said flat caps, independently of the flanged rings.
  5. A reloadable electric fuse comprising an outer cartridge container of infrangible material, removable end caps for the same, a fuse extending between the end caps and surrounded by an inner frangible envelop containing refractory material, and abutments retaining the fuse and its envelop in fixed longitudinal position with respect to the end caps and located one interiorly of the frangible envelop and bearing against the end cap and another exteriorly of the end cap.
  6. A cartridge for a reloadable electric fuse comprising a substantially cylindrical frangible envelop containing refractory material, the link extending axially through said envelop and having its end terminals projecting from the ends thereof, and abutments on the end terminals of the fuse engaging the interior walls of the envelop whereby the fuse link is retained in longitudinal position within the envelop and in turn braces the envelop against collapse.
- In testimony whereof I affix my signature in presence of two witnesses.
- HERMAN H. OSWALD.
